UNITED STATES PATENT OFFICE.

ALBERT W. PEARSALL, OF LOWELL, MASSACHUSETTS, ASSIGNOR TO THE LAMSON COMPANY, OF BOSTON, MASSACHUSETTS, A CORPORATION OF NEW JERSEY.

VACUUM-PLENUM PNEUMATIC-CARRIER-DESPATCH SYSTEM.

1,240,362.

Specification of Letters Patent. Patented Sept. 18, 1917.

Application filed December 3, 1914. Serial No. 875,242.

To all whom it may concern:

Be it known that I, ALBERT W. PEARSALL, a citizen of the United States, residing at Lowell, in the county of Middlesex and

5 State of Massachusetts, have invented certain new and useful Improvements in Vacuum - Plenum Pneumatic - Carrier - Despatch Systems, of which the following is a specification.

10 This invention relates to pneumatic carrier despatch systems and more particularly to a system of this character in which carriers are transmitted outwardly from one station to a second by means of compressed air while carriers are reversely transmitted from said second station to the first by suction or vacuum, so called.

The invention has for one of its objects the provision of means for economizing the 20 power needed for the operation of such apparatus; and this is preferably effected by means of a novel valve mechanism which is adapted to simultaneously control the flow of air through both the outgoing and return tubes of a given one of said stations.

25 This and other objects of my invention will be hereinafter referred to and the novel combinations of elements whereby said objects may be attained will be more particularly pointed out in the claims appended hereto.

30 In the accompanying drawing which forms a part hereof and in which like reference characters designate like parts throughout the several views, I have exemplified a preferred embodiment of my invention; but as I am aware of various changes and modifications which may be made herein without departing from the 35 spirit of the invention, I desire to be limited only by the scope of said claims.

Referring to the drawing:—

Figure 1 is a side elevation of a pneumatic despatch system constructed in accordance 40 with my invention.

Fig. 2 is a detail vertical median section of a valve mechanism which forms a part of said system, and

45 Fig. 3 is an end elevation of the parts shown in Fig. 2.

In Fig. 1 two stations are shown, respectively designated A and B, and the outgoing and preferably normally dead tube from

station A, which leads to station B, and through which carriers are transmitted by 55 means of compressed air, has been designated 1.

The preferably normally dead return tube from station B to station A and through which carriers are transmitted by vacuum, 60 as it is loosely expressed, has been designated 2.

The expression "normally dead" as used in connection with or when referring to the transit tubes, is one in common use in the 65 art and defines that said tubes are normally under or subjected to neither pressure nor vacuum, the air therein, when not in use, being at atmospheric pressure. This type of system, by the way, is much less wasteful of 70 power, since in long lines, especially, there is almost certainly, after a lapse of time, even when installed with great care and at a consequent increase in cost,—more or less leakage of air at the joints, etc.

75 The terminals 3 and 4 at station B are both preferably normally open to the atmosphere while at station A the receiving terminal 5 is normally closed by a valve 6, and the delivering terminal 7 is normally 80 closed by a leather flap valve, or the like designated 8.

The terminal 7 with its receiving shelf 9 is preferably of the type shown, such parts being in common use in exhaust or vacuum 85 carrier despatch systems. The air is exhausted from the transit tube 1 and terminal 7 through an exhaust conduit 10 which is adapted to be placed in communication with a chamber 11 on the left hand end of a 90 casing 12.

The port 13 through which the air emerges from the conduit 10 into said chamber 11 is controlled by a valve 14, which also controls a port 15 through which the air in 95 chamber 11 passes to a pipe 16 which leads to a vacuum drum 17.

Air is exhausted from the latter through a pipe 18 of preferably large diameter in order that a plurality of sets of transit tubes 100 1 and 2 may be operated from a common blower 19 into the intake side of which the pipe or conduit 18 extends.

The pressure side of this blower has correspondingly connected thereto a large pipe 105 19' which leads to a pressure drum 20, to

which in turn are connected one or more pipes 21.

The flow of compressed air from a pipe 21 is controlled by a valve 22, preferably very similar in construction to the valve 14; valve 22 normally covering the port 23 which when open permits the air to flow from pipe 21 into a chamber 24 between valves 14 and 22.

10 When valve 22 is in its open position the air escapes from chamber 14 through a port 25 and via a pipe 26 to the despatching terminal 5.

15 Valves 14 and 22 are fixedly mounted with respect to each other, upon a hollow spindle or shaft 27 and these valves are hence slidably movable together from the position in which they are shown in full lines in Fig. 2 to their dotted line positions, in the direction of their common axis when shaft 27 is moved to the right.

20 The left hand end of this shaft is threaded into a cup 28 the flange of which normally is in engagement with the left hand head 29 of the cylindrical casing 12.

25 Within the cup 28 is a plunger or piston 30 to which is connected a piston rod 31; the latter extending through the hollow shaft 27 and carrying upon its right hand end a valve 32.

30 In order to center the rod 31 in shaft 27, the ends of said rod have preferably substantially the same diameter as that of the interior of shaft 27; but between these extremities rod 31 is preferably reduced to provide an air passage 33 therearound and a hole 34 is formed in the left hand end of shaft 27 to afford communication between this passage 33 and the chamber 11, above referred to; while correspondingly a hole 35, just beyond the valve 22, places passage 33 in communication with a chamber 36, one wall of which is formed by said valve 22 and an opposite wall of which is formed 45 by a diaphragm 37.

35 In addition to the openings 34 and 35, a groove or slot 38 is cut in lengthwise through the right hand head or end of the rod 31, said head being also turned down 50 as at 39 to facilitate the free flow of air past the valve 32 when the latter is in its open position.

40 As shown in Fig. 2 the walls of the chamber 36 are preferably made a part of the casing 12, but the dome-like cap or head 40 at the right hand end of said casing is preferably made readily removable from the casing in order to permit of access to the latch and toggle parts in chamber 36, hereinafter referred to, and in order to permit of the ready insertion or removal of the diaphragm 37, which is clamped between the flanges of the casing 12 and dome 40.

45 The chamber 41 to the right of the dia-

phragm 37, is preferably made as large as 65 practicable for reasons hereinafter indicated, and a readily opened flap valve 42, of flexible leather or the like, covers a hole 43 through which the air in dome 41, even if but slightly compressed above atmospheric pressure, may escape.

50 A small passage 44 nearly closed by a timing valve 45 permits of a slow seepage of air through, for example, a passage or hole 46, which communicates with passage 44, into the chamber 41, when a partial vacuum has been formed in the latter.

55 Slidably mounted upon the right hand end of the tubular shaft 27 is a sleeve 47 which is preferably flanged as indicated, at 60 its right hand extremity, to adapt it for engagement with the central portion of the diaphragm 37 to the end that said diaphragm shall not be cut thereby, but rather may flex around a smoothly curving surface. 65

70 Upon the other side of the diaphragm is a dished plate 48, correspondingly adapted for engagement with said diaphragm; the flange of the sleeve 47, diaphragm and said plate 48 being all riveted together as at 49. 75

80 It is also preferred to provide lugs 50 in the interior of the dome, against which the dish 48 may come to rest. Sleeve 47 carries lugs pivotally connected to which at 85 are links 52, which constitute elements 90 of the toggles hereinafter referred to.

85 Preferably upon opposite sides of the chamber 36 are recesses 53 within which are pivoted as at 54, latch elements 55; said elements preferably being secured to the pins 100 upon which they are mounted so that the latter rotate with said elements, and each of said pins having connected thereto a spring 56 which tends to hold the latch parts in their full line positions, as shown 105 in Fig. 2.

90 Adjustable stops 57 are also preferably provided to limit the outward swing of the latches, and thereby to maintain out of dead center, the respective sets of pivoted pins 110 51 and 54 and the pin 58 which connects each link 52 with the rearwardly projecting arm of the corresponding latch element. It is also preferable to provide slots in the links 52 in which ride these pins 58, as indicated in said figure.

95 The left hand ends of the latch elements are adapted for engagement with an annular rib 59 which extends around in the interior of the valve 22; the latter being preferably hollow as shown. A helical spring 60, disposed around the right hand end of the shaft 27 normally urges said shaft, and thereby the valves 22 and 14 mounted thereupon, toward their left hand positions, in which said valves close the ports 13, 15, 23 and 25; the other extremity of this spring bearing against the edge of the sleeve 47.

and driving the latter, together with diaphragm 37, and dish 48 toward their right hand positions.

The lugs 50, above referred to, serve to limit this movement of the sleeve and diaphragm, while, as previously stated, the cup 28 affixed to the other end of shaft 27, limits the left hand movement of the valves and shaft by engaging the cap or cover plate 29.

This cover plate has screwed thereinto a pipe or nipple 61 which may be placed in communication with a pressure supply pipe 62 by opening a valve 63 in the manner hereinafter described.

The pipe 62 preferably extends to a tank 64 which may be filled with compressed air, and when valve 63 is opened compressed air escapes from said tank into the space between the piston 30 and cap 29, thereby driving said piston together with its rod 31, to the right.

A relatively weak spring 65 ineffectively resists this movement and tends to return said piston to its left hand position as soon as the pressure upon said piston is relieved.

The right hand movement of piston 30 first opens the valve 32 and thereafter drives the shaft 27 with its attached parts to the right. This opens the ports 13, 15, 23 and 25 and causes the latch elements 55 to engage the valve 22 whereby to lock both valves in their open positions.

Compressed air now flows from pipe 21 through chamber 24 into pipe 26, while the air in the pipe 10 becomes rarefied as it escapes via chamber 11 and pipe 16 to the vacuum drum 17.

The partial vacuum thus formed in chamber 11 causes a flow of air past the open valve 32 from the chamber 41 in the dome, through the slot 38, passage 33 and hole 34 into said chamber 11, and thence out through pipe 16 until the pressure of air in chamber 41 has been reduced substantially to that in the exhaust conduit 10.

Further, owing to the fact that the chamber 36 is also in communication with the passage 33, the air upon the left hand side 50 of the diaphragm 37 will also be partially exhausted, so that the pressure upon opposite sides of said diaphragm will be substantially equal.

As soon as the valve 63 is permitted to move to its closed position, the compressed air supply to the pipe 62 is of course cut off and the air under pressure to the left of piston 30, thereupon escapes through the opening 66, whereupon spring 65 returns the piston to its left hand position and closes the valve 32.

Now, while chamber 36 is still in communication with the exhaust, chamber 41 no longer has air exhausted therefrom, while

air slowly seeps into said chamber past the timing valve 45.

The advantage of providing a large chamber 41 is now apparent since it will take considerable time for this chamber to fill with air at a pressure sufficiently above that in chamber 36 to drive the diaphragm with its attached sleeve 47 to the left against the action of the compressed spring 60.

Had the chamber 41 been located in a receptacle which would quite closely conform to the diaphragm 37, when the latter is in its right hand position, as is quite common practice in pneumatic timing devices used in pneumatic despatch apparatus, it is evident that air at a sufficient pressure to operatively displace the diaphragm, would quite speedily be accumulated; and hence I particularly desire to direct attention to this provision of the commodious chamber 41 since thereby a timing period of relatively great duration is secured.

This lengthy timing of the closure of a valve for controlling the flow of air through a transit tube is frequently of great importance and especially when the length of the line is considerable.

When the diaphragm 37 finally does begin to move toward the left, at first its movement is idle but as soon as the pins 58 are seated against the inner ends of the slots 95 in which they ride, the latch elements 55 begin to rotate toward their dotted line positions, whereby to release the valves 14 and 22.

As soon as these latches clear the rib 59, said valves are abruptly closed by the action of spring 60, whereupon the exhaust of air from chamber 36 ceases, and said chamber 36 is placed in communication with the atmosphere by the removal of the valve 22 from its position above a port 67, permitting spring 60 to drive the diaphragm to the right; the air in chamber 41 being brought to atmospheric pressure through the opening of the flap 42.

I shall now consider the preferred mode of operating the valve 63, which is preferably of the balanced type. The stem 68 of this valve is preferably of iron and extends up into the solenoid 69, which when energized by current from the battery 70 has sufficient strength to lift said valve to its open position. At station A, the spindle upon which is mounted the valve 6 carries a contact 71 which is rotated into engagement with a contact 72 each time that the valve is raised by the insertion of a carrier into the terminal.

Current thereupon flows from the battery through a wire 73 to the solenoid 69 and from thence through a wire 74 to contacts 72 and 71, whence it flows via wires 75 and 76 back to the battery.

Solenoid 69 may also be controlled from station B by means of the usual contact operating arm 77 located in the path of the carrier adjacent the mouth of the terminal 5 3 which effects a closure of circuit in the contact box 78, in a known manner, completing the following circuit:

From the battery 70 current flows through wire 73, solenoid 69 and wire 74 to a wire 10 79, thence through the contacts in box 78 and a return wire 80 to wire 76 and the battery. In other words every time that a carrier is despatched either from station A or 15 station B, solenoid 69 is momentarily energized to effect the opening of valve 63; the valve of course being allowed to close as soon as the carrier is despatched from the terminal.

Should the valves 14 and 22 be in their 20 open positions and latched by the elements 55, when a second carrier is to be despatched from one or the other of the stations, the effect of this second opening of valve 63 before the return of the shaft 27 to its left 25 hand position, is to momentarily again open the valve 32 by the inward movement of the piston 30 into its cup; which effects an equalization of pressure upon opposite sides of the diaphragm 37, the air already 30 accumulated in the chamber 41 passing through the slot 38, passage 33 and opening 34, into chamber 11.

The motor 81 which drives the blower 19 may be a continuously driven one and indeed where a number of transit lines are connected with the drums 17 and 20 and where as a result the motor is of relatively 35 large size as compared to that required for operating a single line of transmission tubing, it should be continuously operated to avoid the loss incident to starting it from time to time, whenever a carrier is despatched. To the right of the blower is shown a panel 82, and somewhat diagrammatically the electric connections to the motor; the diagram of the armature and shunt winding being thus shown in order to avoid 40 multiplication of figures. This panel comprises a shunt field rheostat 83 controlled 45 by an arm 84 pivoted upon the panel at 85.

The left hand end of the rheostat arm carries a bracket upon which is mounted a roller 86, which is adapted to ride upon a small table 87 carried upon the upper end 50 of a rod 88. This rod has secured thereto a piston 89 which rides in a cylinder 90 and suitable weights 91 are attached to the lower extremity of said rod.

The upper end of the cylinder 90 is connected by a pipe 92, preferably but of course not necessarily, with the exhaust conduit 18, so that when the valves 14 and 22 are closed, a sufficient vacuum will be established in the upper end of the cylinder 90

to hold the piston in its uppermost position 65 against the action of the weights 91.

This of course will hold the arm 84 in the limiting position into which it can be rotated clockwise, thereby cutting resistance 70 out of the shunt field 93 to reduce the speed 75 of the motor to a minimum.

Whenever valves 14 and 22 are opened, however, the vacuum in the conduit 18 is partly broken and the piston 89 descends a distance corresponding substantially to the 75 rise in pressure upon the exhaust side of the blower. This action permits the arm 84, weighted as it is by the bracket which carries the roller 86, to rotate counter-clockwise to cut in resistance in the shunt field 80 and correspondingly speed up the motor to a greater or less amount.

It is obvious that if but a single line of transit tubing has been thrown into operation, the speed of the motor will be increased 85 but the requisite amount to operate such line, while if a plurality of the lines which are in communication with drums 17 and 20 are simultaneously thrown into operation, the speed of the motor will rise to 90 meet such condition.

The electrical circuits controlled by the respective parts mounted upon this panel board need not be herein further discussed 95 since boards of this description are in common use.

Accordingly reference will merely briefly be made to certain of the wires and parts to identify the same. The leads to the armature have been designated 94 and 95 and 100 the ends of these leads are shown by dotted lines extending from the motor as well as in full lines in the wiring diagram. The part designated 96 is the resistance which is cut out of the armature circuit when the motor is started by means of the starting lever 97, and the device designated 98 is the electro-magnetic latching device for holding the starting arm in its right hand position 105 as long as the motor continues in operation. 110

As previously stated, in view of the fact that these panel boards and the connections leading therefrom to the armature and shunt fields of the motor are in common use a further description of said connections herein 115 is omitted.

I particularly desire, however, to emphasize the fact that while control of the motor which drives the blower of an exhaust pneumatic despatch tube system by means of 120 such a cylinder as that designated 90 and a connection thereto from the exhaust drum, whereby to cut in or cut out resistance in the motor shunt field, is already known, nevertheless it has never been found practicable heretofore, to the best of my knowledge, to provide such a device in connection 125 with a vacuum-pressure system, although it

has been known to use a panel board for the vacuum side and a second panel board for the pressure side whereby to jointly control the motor from both sides.

5 Such a control has not been found to be altogether satisfactory since a number of lines on the vacuum side may be simultaneously in operation while but perhaps one or even none will be in use on the pressure side of the blower.

10 This provision, for example, of a single panel with its connections whereby to control a vacuum-plenum system together with the valve combination shown and time element mechanism for the same, enables a material reduction in cost of apparatus to be effected, together with increased efficiency; since the terminals at station B, for example, need be only of the simplest description 15 and without valves, while the disposition of the blower, in effect, midway between the terminal 3 and the terminal 4, permits of the use of a smaller motor than is ordinarily possible when the transmission of 20 carriers in both directions is effected either solely by means of compressed air or solely by means of vacuum.

Having thus described my invention what I claim is:—

30 1. In a vacuum-plenum carrier despatch system, the combination of a normally dead transit tube having a receiving station substantially at one end thereof and a carrier delivery station at the other end thereof, an 35 exhaust conduit therefor, a pressure transit tube, a compressed air supplying conduit therefor, means to rarefy the air in the first of said conduits and to compress air for the second of the same, and means adapted 40 to substantially simultaneously establish communication between said transit tubes and their respective conduits.

2. In a vacuum-plenum carrier despatch system, the combination of a normally dead 45 transit tube having a receiving station substantially at one end thereof and a carrier delivery station at the other end thereof, an exhaust conduit therefor, a pressure transit tube, a compressed air supplying conduit 50 therefor, means to rarefy the air in the first of said conduits and to compress air for the second of the same, valve mechanism adapted to substantially simultaneously establish communication between said transit tubes 55 and their respective conduits, and means to control said valve mechanism.

3. In a vacuum-plenum carrier despatch system, the combination of a normally dead transit tube having a receiving station substantially at one end thereof and a carrier delivery station at the other end thereof, an exhaust conduit therefor, a pressure transit tube, a compressed air supplying conduit 60 therefor, means to rarefy the air in the first

of said conduits and to compress air for the 65 second of the same, and means to substantially simultaneously disestablish communication between said transit tubes and their respective conduits after such communication has been established.

70 4. In a vacuum-plenum carrier despatch system, the combination of a transit tube, an exhaust conduit therefor, a pressure transit tube, a compressed air supplying conduit therefor, means to rarefy air in the 75 first of said conduits and to compress air for the second of the same, two stations between which said tubes extend, valve mechanism to substantially simultaneously establish communication between said transit 80 tubes and their respective conduits, and means to control said valve mechanism from either of said stations.

85 5. In a vacuum-plenum carrier despatch system, the combination of a normally dead transit tube having a receiving station substantially at one end thereof and a carrier delivery station at the other end thereof, an exhaust conduit therefor, a pressure transit tube, a compressed air supplying conduit 90 therefor, means to rarefy the air in the first of said conduits and to compress air for the second of the same, valve mechanism adapted to substantially simultaneously establish communication between said transit tubes 95 and their respective conduits, time element means to automatically actuate said valve mechanism to disestablish said communication after the lapse of a period of time determined by said means, and means to re-time said time element means, to provide 100 for the proper transmission of successively despatched carriers.

105 6. In a vacuum-plenum carrier despatch system, a transit tube extending between two stations and having in one of said stations a valved terminal and an exhaust conduit connected to this latter, whereby carriers may be propelled from the other of said stations substantially all the way to said first station by atmospheric pressure, the valve in said terminal being normally closed and the terminal of said tube at said other station being normally open, a second transit tube extending between said stations and having at the station first mentioned a valved terminal and a second conduit for supplying air under pressure to the latter, to despatch carriers therefrom toward the second station, said second transit tube, like the first, 110 being normally open to the atmosphere at said second station, a blower or pump having air directing connections between its intake side and said exhaust conduit and between its outlet side and said second conduit,

115 and valve mechanism adapted to substantially simultaneously establish a flow of air from said second station through said 120 125

first tube to its exhaust conduit and a corresponding flow of air from said second conduit through said second tube to said second station.

- 5 7. In a vacuum-plenum carrier despatch system, the combination of two normally dead transit tubes, one for transmitting carriers by compressed air and the other by air at substantially atmospheric pressure, a 10 pressure drum and a vacuum drum, connections between said drums to the respective tubes, valves in each of said connections to control the flow of air through said tubes and means to substantially simultaneously 15 set both of said valves in their open or in their closed positions.

8. In a vacuum-plenum carrier despatch system, the combination of two normally dead transit tubes, one for transmitting carriers by compressed air and the other by air at substantially atmospheric pressure, a 20 pressure drum and a vacuum drum, connections between said drums and the respective tubes, valves in each of said connections to 25 control the flow of air through said tubes, and electrically controlled means to set said valves simultaneously each in its open position.

9. In a vacuum-plenum carrier despatch system, the combination of two normally 30 dead transit tubes, one for transmitting carriers by compressed air and the other by air at substantially atmospheric pressure, a pressure drum and a vacuum drum, connections between said drums and the respective 35 tubes, valves in each of said connections to control the flow of air through said tubes, and means to set said valves simultaneously each in its open position.

10. In a vacuum-plenum carrier despatch 40 system, the combination of two normally dead transit tubes, one for transmitting carriers by compressed air and the other by air at substantially atmospheric pressure, a pressure drum and a vacuum drum, connections 45 between said drums and the respective tubes, valves in each of said connections to control the flow of air through said tubes, means to set said valves in their open positions, and means to automatically close both 50 of said valves substantially simultaneously.

11. In means for controlling the flow of air through a vacuum-plenum carrier transmission system, a casing having in communication therewith a set of conduits for conveying air at a pressure below that of the atmosphere and a second set of conduits for conveying air above that of the atmosphere, connected valve parts, mounted on a common axis to control the flow of air through 60 said conduits, pneumatic means for disposing said valve parts in their open positions, and time element mechanism for determining the period during at least which said parts shall remain open and for thereafter

normally insuring the return of said valve 65 parts to their conduit closing positions.

12. In means for controlling the flow of air through a vacuum-plenum carrier transmission system, a casing having in communication therewith a set of conduits for conveying air at a pressure below that of the atmosphere and a second set of conduits for conveying air above that of the atmosphere, valve parts to control the flow of air through 70 said conduits, electrically controlled means for disposing said valve parts in their open positions, means, common to said valve parts for latching said parts in their open positions and time element mechanism for releasing 75 said parts from said latching means. 80

13. In a pneumatic despatch system, the combination of two separate and normally dead transit tubes, a blower or pump, connections between the exhaust side of the latter and one of said tubes and between the 85 outlet side of said blower or pump and the other of said tubes, valve mechanism, normally closing said connections, and means to automatically actuate said mechanism to 90 substantially simultaneously open said connections and to thereafter automatically close the same.

14. In a pneumatic despatch system, the combination of two normally dead transit tubes, a blower or pump, a connection between the exhaust side of the latter and one of said tubes, a connection between the outlet side of said blower or pump and the other of said tubes, a valve in each of said 95 connections, means for substantially simultaneously opening said valves, and co-acting 100 means for simultaneously closing said valves thereafter.

15. In a pneumatic carrier despatch system, the combination of a transit tube with 105 means, including a valve, for controlling the flow of air through said tube, said means having also a fluid pressure operated time element device in which is a chamber of large capacity, one wall of said chamber being formed by a movable partition, the said chamber, even when said partition is in its innermost position therein, still having a relatively large capacity, means for normally permitting only a seepage of air 115 through a wall of said chamber, and normally closed auxiliary venting means to afford communication between said chamber and air outside thereof.

16. In a pneumatic carrier despatch system, the combination of a transit tube with means for establishing a carrier transmitting flow of air through said tube, said means including a fluid pressure operated time element device in which is a chamber of large capacity, one wall of said chamber being formed by a movable partition, the said chamber, even when said partition is in its 125

innermost position with respect to said chamber, still having a relatively large capacity, means for normally permitting only a seepage of air through a wall of said chamber, and normally closed auxiliary venting means to afford communication between said chamber and air outside thereof.

In testimony whereof I have affixed my signature, in the presence of two witnesses.

ALBERT W. PEARSALL.
